UNITED STATES PATENT OFFICE.

RICHARD M. CRAIG, OF SAN ANTONIO, TEXAS.

STATION-INDICATOR.

1,168,170.

Specification of Letters Patent. Patented Jan. 11, 1916.

Application filed March 17, 1914. Serial No. 825,382.

To all whom it may concern:

Be it known that I, RICHARD M. CRAIG, citizen of the United States, residing at San Antonio, in the county of Bexar and State of Texas, have invented certain new and useful Improvements in Station-Indicators, of which the following is a specification.

My invention relates to that class of indicators designed to be mounted within a street car and to display to the passengers the names of the streets passed by the car, and more particularly to certain improvements on the station indicator, illustrated and described in my pending application 15 for electrical indicator for street cars, Serial No. 541,307, filed February 7, 1910, and patent on switch operating mechanism for electric railways, No. 1,140,579, dated May 25, 1915.

One object of my invention is to provide a street car indicator including a band containing street names, which band may also and preferably does contain advertisements, and means for electrically operating or 25 shifting the band at suitable distances along the route, as for instance at the corner of each street, the operation of shifting the band being entirely automatic and not dependent upon any manual actuation.

A further object of the invention is to provide means for automatically reversing the band at the end of a route or any predetermined section of a route, and in this 30 connection to provide means whereby the band may be manually reversed when desired.

A further object of the invention is to provide a street car indicating mechanism wherein the band containing the street 40 names will not only be automatically shifted as above described, but wherein the band will also automatically throw switches as the car approaches a switch without the motor-man or conductor having to operate the 45 switch.

Another object of the invention is to so form the band carrying the street names that it can with equal facility be used either on a straight line, loop line, on a diverse 50 route, or on all of these forms of lines.

Still another object is to so construct the indicating mechanism that it may be operated on a trolley system, third rail system, middle rail system, or where underground 55 conduits are used.

Still another object is to so construct the band and the operating mechanism therefor that the street names or advertisements for three or more routes may be placed on a single band without interference, the band 60 only operating on the route on which it is set to operate.

A further object of the invention is the provision of a band which of itself controls the band actuating mechanism and the 65 switch throwing mechanism and the reversing mechanism, and which does not require the interference of an operator in order to perform its proper functions.

Still another object is to provide electrical 70 actuating mechanism, switch shifting mechanism, reversing mechanism, all controlled by electrical contacts placed upon the band.

A further object is the provision of a belt having alternate spaces for successive 75 streets, the other alternate set of spaces being used for successive streets after the belt has reversed and travels in the opposite direction.

Still another object is to support all of the 80 actuating mechanism shifting the band and actuated by the shifting of the band, so constructed that it is contained within a case, this case being adapted to be slipped into or out of a compartment formed in the car for 85 the case and having electrical contacts leading to the feed wires for the supply of electrical current.

Still another object of the invention is to support the band by means of spools or 90 reels and provide mechanism whereby when one spool is driven to carry the band in one direction, the other spool shall run free.

A further object of the invention is to provide for positively stopping the band 95 with each name clearly in front of the opening through which the street name or advertisement is to be displayed.

A further object is to provide means for sending a momentary current from a feed 100 wire to thereby close a circuit through the belt operating motor.

Other objects will appear in the course of the following description.

My invention is illustrated in the accompanying drawings wherein:

Figure 1 is a top plan view partly in section. Fig. 2 is a section on the line 2-2 of Fig. 1. Fig. 3 is an enlarged view partly diagrammatic showing the manner of elec- 110

trically energizing the motor and reversing the motor. Fig. 4 is a fragmentary perspective underside view of a portion of the controlling and advertising belt and the fingers or contacts whereby the various electrical circuits are closed. Fig. 5 is a fragmentary perspective view of the circuit breaking contacts and the reversing lever. Fig. 6 is a diagrammatic view illustrating the electrical connections from the several contacts, through the motor, the actuating solenoids and the switch actuating mechanism. Fig. 7 is a fragmentary face view of one of the name displaying bands. Fig. 8 is a map showing the layout of the route corresponding to the route indicated by the names on the band shown in Fig. 7. Fig. 9 is a fragmentary face view of a band having a route divided into three sections and indicated thereon. Fig. 10 is a fragmentary detail view showing the arrangement of the trolley contacts and trolleys. Fig. 11 is a fragmentary detail elevation of a modified form of trolley wire contacts and trolley contacts. Fig. 12 is a sectional view showing a modified form of belt.

Corresponding and like parts are referred to in the following description and indicated in all the views of the accompanying drawings by the same reference characters.

Referring now to Figs. 1 and 2, 2 designates a casing of metal, wood or any other suitable material adapted to be disposed in a suitable position within a car and adapted 35 to align with a front opening 3 formed in a box or other suitable housing which may form part of the permanent framework of the car. It will be understood that the front 4 which is illustrated as forming part of the 40 housing within which the casing 2 is disposed, might be made as part of the casing. The reason for making the casing 2 separate from the housing inclosing the casing will be later stated. The opening 3 is covered 45 by a pane of glass 5 through which the street names and advertisements displayed upon an advertising band may be read. The advertising band A passes behind the pane 5 and at its ends is connected to the reels 50 or spools 6 and 7, each mounted on a vertically disposed spindle. The band A is conducted to and from these reels or spools 6 and 7 by means of rollers 8 disposed one on each side of the display opening. The reels 55 6 and 7 are operated by means of an electric motor 9 of any suitable form, the shaft of this motor being formed with a worm 10 engaging with a worm wheel 11 mounted upon a shiftable shaft 12. As illustrated, 60 this shaft 12 at its middle portion is many sided and the opening in the gear wheel 11 is also many sided so that while the shaft can slide relative to the gear wheel 11, rotative movement communicated to the gear wheel will rotate the shaft. The wheel 11 is

supported in suitable bearings mounted on brackets 13.

Disposed adjacent one end of the shaft 12 is a short shaft 14 carrying upon it a sprocket wheel 15 over which a sprocket chain 16 passes to the spindle of the reel 7, and mounted upon the adjacent end of the shaft 12 is a bevel gear wheel 17 adapted to mesh with a bevel gear wheel 18 carried upon the shaft 14 when the shaft 12 is in one of its shifted positions. Mounted adjacent the other end of the shaft 12 is a shaft 19 carrying at one end a sprocket wheel 20 over which passes a sprocket chain 21 to the spindle of the reel 6. This shaft 19 also 80 carries upon it a bevel gear wheel 22 with which a bevel gear wheel 23 mounted upon the shaft 12 engages. It will be seen from Fig. 1 that when the shaft 12 is shifted toward the right in Fig. 1, the gear wheel 17 85 will engage with the gear wheel 18 and the reel 7 will be rotated to wind up the band 6, and that when the shaft 12 is shifted in a reverse direction or toward the left in Fig. 1, the gear 23 will engage with the gear wheel 22 while the gear wheel 17 will be shifted out of engagement with the gear wheel 18, and that under these circumstances the reel 7 will run idle while the reel 6 will be positively rotated to wind up the 90 film upon the reel.

For the purpose of automatically shifting the shaft 12 into one or the other of the positions above referred to in order to reverse the movement of the band A, I provide the reversing lever 24 as shown in Fig. 1, this reversing lever being pivoted at 25 on any suitable support and being slotted at its end adjacent the shaft 12 as at 26. The shaft 12 has projecting from it a pin 105 27 which engages through the slot in the lever 24. The outer end of the lever 24 is slotted as at 28, and passing through this slot is a pin 29 projecting upward from the core 30 of a pair of solenoids. One of 110 the solenoids is designated 31 and the other 32. When one of these solenoids is actuated as for instance the solenoid 31, the outer end of the lever will be drawn to the left in Fig. 1 and the shaft 12 will be shifted to the right. When, however, the other solenoid 32 is actuated, a reverse movement will occur and the shaft will be shifted so as to operatively connect the reel 6 with the driving mechanism. As illustrated in Fig. 120 6, the two solenoids are each connected by means of a wire 33 to a common conductor 34 which connects to a lead wire 35, which in turn engages a small shoe or trolley wheel 36 adapted to take current from the trolley wire or a third rail at regular intervals as for instance at street crossings in the manner illustrated in my prior application, Serial No. 541,307 before referred to. Current is directed through one or the 130

other of these solenoids 31 or 32 by means of the band A as will be later described. Current is carried to the motor 9 by a lead wire 41 (see Fig. 6) and connections disposed in circuit between said lead wire and the motor 9 as will be later described.

For the purpose of causing a reversal of the lever 24 and for causing an intermittent energizing of the motor 9, and the stopping of said motor, and also for causing the adjustment of track switches, the belt A as illustrated most clearly in Fig. 4 is preferably formed with a plurality of openings 38 and this band or belt A passes between a common contact bar 39 and a plurality of fingers 40, 40^a, 40^b, 40^c, 40^d and 40^e corresponding in number to the number of the openings 38. The openings in the belt are designated respectively 38, 38^a, 38^b, 38^c, 38^d and 38^e corresponding to the fingers before mentioned. While in Fig. 4 I have illustrated all of these openings as being arranged in line with each other, it is to be understood that this is simply for clearness of illustration and to show the position of the openings relative to each other and to the fingers. As a matter of fact, however, these openings will be arranged out of transverse alinement with each other as indicated most clearly in Fig. 7. The openings 38 and 38^a are for the purpose of opening and closing a switch respectively. The openings 38^b and 38^c are for the purpose of stopping the motor upon the travel of the band in one direction and for stopping the motor on a travel of the band in the other direction. The openings 38^d and 38^e are respectively for reversing the movement of the belt when the belt is initially moving downward and for reversing the movement of the belt when the belt is initially traveling upward. All of the openings 38 and 38^a are arranged in vertical alinement with each other as seen clearly in Fig. 7.

One side of the motor 9 is connected by means of a wire 41 to the general car circuit and the other side of the motor is connected by means of the wires 42 and 43 to a contact 44. Coacting with this contact 44 is a movable contact member 45 which is pivoted at one end as at 46 and normally held from engagement with the contact 44 by means of a spring 47. This contact 45 has a plunger 48 which operates within a solenoid 49. This solenoid is operatively connected on one side to a ground by a wire 50 and on its other side is electrically connected through a wire 51 and a movable contact switch 52 to the feed wire 37. Thus when a circuit through the solenoid 49 is completed, the contact member 45 will be drawn inward against the contact 44. This contact 45 is connected by means of a wire 53 and through a resistance 54 to the gen-

eral car circuit. When the solenoid 49 is energized and the contact 45 drawn into engagement with the contact 44, current will pass from the general car circuit through the motor 9 by way of wire 53 to 70 the contact 45 thence through contact 44 and back by the wires 48, 42 and 41 and the motor will be operated.

For the purpose of holding the contact 45 in position against the contact 44, I provide a latch 55 pivoted at its rear end, this latch forming an armature coacting with the two electro-magnets 56 and 56^a. When either one of these electro-magnets is energized, the latch 55 will be raised and the contact member 45 will be drawn out of its engagement with the contact 44. These magnets 56 and 56^a are both connected to a return wire 57 which leads to a wire 58, which in turn leads to a local battery 59 85 and connects to the common contact member 39.

The magnet 56 is connected by means of a wire 60 to a metallic contact 61 as illustrated most clearly in Fig. 5 and this contact coacts with a metallic contact member 62 from which a wire 63 leads to the contact finger 40^c corresponding with the opening 38^c in the band. Thus when this opening 38^c reaches the contact bar 39, the finger 40^c will spring into contact with the contact member 39 and the circuit will be completed and thus the magnet 56 will be energized, the magnet 56^a remaining deenergized, however. The interruption in the circuit 100 between the contact member 61 and the contact member 62 is closed by means of a bridge contact 64 mounted upon the lever 24 as shown in Fig. 5. When the lever 24 is in the position illustrated in Fig. 6, this portion of the circuit through the magnet 56 is closed. When, however, the lever 24 has been shifted over to reverse the movement of the band by the action of the solenoid 32, then the circuit through the magnet 56 is broken for a purpose to be later stated.

The magnet 56^a is connected by means of a wire 65 to a contact member 66 which coacts with a contact member 67 spaced from the contact member 66 and connected by means of the wire 68 to the finger 40^b which coacts with the perforation 38^b in the band. When the band is moving upward, the lever 24 will be in the position shown in Fig. 6. As a consequence, the circuit through the magnet 56^a will be broken at 66 and 67 but the circuit through the magnet 56 will be bridged at 63 and 61. As a consequence when the band has moved sufficiently to bring the perforation 38^b opposite the finger 40^b, a circuit will be closed from the local battery 59 through wires 58 and 57, through the magnet 56, through wire 60, contacts 61, 64 and 62 to wire 63, thence 133

to the finger 40^a, thence through the perforation 38^a in the belt to the common contact bar 39 and thence back by wire 58 to the battery 59, thus causing the magnet 56 to be momentarily energized. The energizing of this magnet 56 will cause the latch 55 to rise, releasing the contact member 45 and breaking the car circuit through the motor thus causing a stoppage of the motor 10 until the solenoid 49 is again energized in the manner heretofore stated. When the band is moving downward, however, exactly the same operation occurs except that in this case the lever 24 is reverse from the 15 position shown in Fig. 6. The contact member 64^a bridges the interruption 66 and 67 and in this case when the perforation 38^b reaches the finger 40^b, a circuit will be closed from the local battery 59 through the magnet 56^a which will cause the lifting of the latch 55 and the breaking of the car circuit 20 through the motor.

For the purpose of reversing the lever 24 automatically at the end of a route or 25 at any desired point so as to reverse the movement of the band, I provide the two contact fingers 40^a and 40^b coacting respectively with the openings 38^a and 38^b in the band. For the purpose of energizing one 30 or the other of the solenoids 31 and 32 I connect both of the solenoids by means of the wires 34, 35 and 33 to the trolley contact 36. The solenoid 32 is connected by means of the wire 69 to a contact point 70 normally 35 out of electrical engagement with a pivoted switch bar 71. This bar is pivoted at 72 and its outer end is drawn downward by means of a spring 73. The bar 71 at its pivotal point is connected by means of the 40 wire 74 to the wire 37 and thence returns to the trolley contact 36^a. If the switch contact 71 is in electrical engagement with the contact 70, current will thus pass from the trolley contact 36^a by way of wires 37 45 and 74 to the switch bar 71 thence to the contact 70, thereby by way of wire 69 to the solenoid 32, thence by wires 33, 34 and 35 back to the trolley contact 36.

The solenoid 31 as before stated is connected on one side by the wires 33, 34 and 35 to the trolley contact 36, and on the other side is connected by wire 75 to a contact 76 coacting with the switch contact bar 77 which is pivoted at 78 and held normally 50 out of electrical engagement with the contacts 76 by the spring 79. From the pivotal center of this bar extends a wire 74^a which connects to the wire 74 and from thence the current passes by wire 37 to the trolley contact 36^a. Thus when the switch contact 77 is electrically connected to the contact 76, a circuit will be completed through the solenoid 31 to energize this solenoid. Normally both of the switch contacts 71 and 77 55 are out of electrical engagement with the

contacts 70 and 76 respectively and therefore the circuits through both of the solenoids 31 and 32 is broken.

The contact finger 40^a is connected by means of the wire 80 to a contact member 81 which coacts with a contact member 82, the gap between these two contact members being completed by the bridging contact member 83 carried by the lever 24 as illustrated clearly in Fig. 5 when the lever is 70 in the position shown in Fig. 6. Under these circumstances when a perforation 38^a comes beneath the finger 40^a, a circuit is 75 closed from the battery 59 by wire 58, bar 39, contact finger 40^a, wire 80, thence 80 through contact members 81, 83 and 82 to wire 84, through the electro-magnets 85, thence by wire 86 to the return wire 58, thence back to the battery, energizing the 85 magnets 85 and drawing down upon the switch bar 71. This closes the circuit through the solenoid 32 and this solenoid being energized will shift the lever 24 toward the right in Fig. 6. This will reverse 90 the motion of the band as previously described and whereas the band was previously moving downward, or in one direction, it will now be reversed in its movement and will move upward or in the other direction. When it has traveled in this last named direction as far as predetermined, a perforation 38^a will come beneath the finger 40^a and a circuit will be closed from the battery 59, wire 58, contact bar 39, finger 40^a to wire 87, thence by wire 87 to the contact member 88, 95 across the bridge piece 83^a to contact 89 thence by wire 90 to the electro-magnet 91, thence by wire 92 to the return wire 58 and back to the battery, thus energizing the magnet 91 drawing downward upon the switch bar 77 and closing a circuit through the solenoid 31, again acting to reverse the direction of movement of the band.

For the purpose of actuating a track switch automatically and without the intervention of the operator and by means of the band, I provide a track switch indicated at B in Fig. 6, which is mounted upon a core 93, this core having its ends coacting with the solenoids 94 and 94^a respectively. Both 110 of these solenoids are connected to a common return wire 95 which extends to the trolley wire. The solenoid 94 is connected by means of the wire 96 to the trolley contact member 97 while the solenoid 94^a is connected by 115 means of wire 98 to the trolley contact member 99. The perforations 38 and 38^a and the fingers 40 and 40^a are for the purpose of actuating the switch, that is, for the purpose of energizing one or the other of the 120 solenoids 94 or 94^a. When a perforation 38 comes beneath the finger 40, a circuit is 125 completed through the battery 59 by way of wire 58, through the common contact bar 39 to finger 40, thence by wire 100 through 130

an electro-magnet 101, thence by wire 102 to the return wire 58 with which it is connected through the medium of a hand operated switch 103, this switch being normally in closed position. When, therefore, the circuit is completed through the magnet 101 to energize this magnet, the magnet will draw down upon the switch bar 52, thus causing said bar to break circuit with wire 37 thus 5 breaking the circuit through the solenoid 94, the circuit remaining completed however through the solenoid 94^a, thus causing the switch to shift to the right in Fig. 6. If, however, a perforation 38^a comes opposite 10 the finger 40^a, a circuit is completed from the battery 59 by way of wire 58, through the common contact bar 39, the finger 40^a, thence by wire 104 to the electro-magnet 105, thence by wire 106 to the return wire 58. This will attract the switch bar 52^a forming 15 the armature of the magnet 105 and break connection between the said switch bar and the terminal of wire 35 and thus the circuit will be broken through the solenoid 94^a 20 causing this solenoid to become dead while the other solenoid is active. It will be understood, of course, that when the trolley contacts 36 and 36^a reach the contacts 99 and 97 which are electrically connected to the trolley wire, third rail or other source of 25 power, a circuit will be momentarily completed through both of the solenoids unless a circuit through one of the solenoids is broken. If the circuit is completed through 30 both of the solenoids, both will be equally energized and therefore the switch will not be shifted. It is by breaking the current through one of the solenoids and leaving the other solenoid energized that I secure a shifting of the switch. The broad principle 35 of this switch shifting mechanism is described and claimed in my pending application. Serial No. 672,379, heretofore referred to.

40 The mechanism heretofore described and illustrated in Figs. 1, 2 and 6, is intended to be used with a motor driven by an alternating current and in this case it is necessary to provide means for mechanically reversing the direction of movement of the band. Where, however, the motor can be reversed there is no necessity of using other means for reversing the movement of the band. In 45 Fig. 3 I have shown a system of wiring adapted to be used with a direct current and where the motor may be reversed by reversing the connections to the motor. In this view, A designates the band which is of exactly the same form as the band heretofore described and provided with the same perforations. This band passes over the reels 6^a and 7^a. The spindles of these reels have mounted upon them the ratchet wheels 107 and 108. The ratchet wheel 107 has its 50 teeth reversely placed to the teeth on the ratchet wheel 108. Mounted on the reel 6^a is a pawl 109 engageable with the ratchet wheel 107 so as to cause unitary movement of the ratchet wheel and the reel 6^a in one direction but permit the ratchet wheel to 55 run freely in the other direction. The reel 7^a is provided with a pawl 110 which engages the ratchet teeth on wheel 108 for movement in one direction but permits the reel to run freely upon a movement of the 60 ratchet wheel in the other direction. The ratchet wheels 107 and 108 both carry sprocket wheels 111 over which passes a sprocket chain 112. This chain passes over a sprocket wheel 113 carried upon a spindle 65 114, and mounted upon this same spindle is a toothed gear wheel 115 engaged by a worm 116 formed upon a shaft 117 which is driven by the motor 118. It will be seen that if the motor shaft 117 moves in one direction, the wheel 115 will be given a clockwise movement and under these circumstances the reel 6^a will be actuated while the reel 7^a will run free. Upon a rotation of the shaft 117 in a reverse direction, the 70 wheel 115 will move reversely and the reel 7^a will be positively actuated and the reel 6^a will run free. Thus the reel which constitutes the take-up reel will be positively actuated while the opposite reel will run free, 75 each reel 6^a and 7^a becoming alternately the take-up reel.

80 The mechanism for reversing the movement of the band includes the opposed solenoids 31^a and 32^a corresponding to the solenoids 31 and 32 in Fig. 1. The core 30^a of these solenoids is operatively connected to the lever 24^a which is pivoted at 25^a. The lever carries upon it the spaced contacts 119 and 120 which coöperate with the contacts 121 and 122 when the lever is in one position, and with the contacts 123 and 124 when the lever is in the position shown in Fig. 3. The wires 125 and 126 leading from the 85 binding posts to the motor are connected respectively to the contacts 120 and 119. The wire carrying the positive current from the car wiring system is designated 127 and this wire leads to the contact 121 and by way of wire 128 to the contact 124. The wire carrying the negative current is designated 129 and leads to the contact 122 and to the contact 123. It will thus be seen that when the lever 24^a is thrown to the left as in Fig. 3, the positive contact 123 on that side will be 90 connected to the wire 126 and the negative contact 124 will be connected to the wire 125. When, however, the lever is reversed from the position shown in Fig. 3, the connection of the motor to the positive and negative wires will be reversed, thus causing a 95 reversal of the rotation of the motor. Otherwise than as above described, the construction of the apparatus will be precisely the same as that illustrated in Figs. 1 and 100 125 130

6. Hence it is not believed necessary to show the complete system of wiring as this is fully illustrated in Fig. 6 and has been described previously.

5 As illustrated in Fig. 10, the trolley wire 130 is connected to the longitudinally extending contacts 97 and 99 and a trolley pole 131 carries a bracket 132 within which the contact rollers 36 and 36^a are mounted.

10 These contacts 99 and 97 are disposed at intervals along the line of the railroad and preferably at the intersection of streets or wherever a switch is to be shifted or the belt is to be reversed.

15 In Fig. 7 is shown a face view of a portion of a band, this band being designed to contain the names of the streets passed by the car and also operating the several instrumentalities heretofore described. The band 20 as illustrated in Fig. 7 is designed to be used on a route such as that shown in the map-like view, Fig. 8. As illustrated, this band is formed on one margin with the several perforations 38, 38^a, 38^b, 38^c, 38^d and 38^e 25 shown in Fig. 4. The perforations 38^e and 38^d are for reversing the travel of the band. The perforations 38^b and 38^c are for stopping the motor upon the travel of the belt upward or downward, and the perforations 30 38 and 38^a are for actuating a switch either upon a movement of the band upward or downward. The action of the band may be best understood by reading Fig. 7 in connection with Fig. 8. The beginning of the 35 route is marked by the letter X and the car is supposed to move in the direction of the arrow. The first street crossed after starting is Broadway; the next street is Olive; the next Dearborn; the next Castle, and the next Wall. After passing Wall street, the car passes onto a portion of the line where the cars run both ways on the same street until the cars reach Madison street. Here the outward bound car diverges and passes 40 around a loop crossing Madison, Market and Water streets. It then again intersects with the main line and passes along this main line to any desired extent, the car being shown as stopping beyond Randolph street. Here 45 the belt is again reversed; the car travels back again in the direction of the arrows, throwing a switch at Clark street and crossing Fulton and Humboldt streets, again throwing the switch at Madison street and continuing past Spring, State and Wall 50 streets throwing a switch at this latter point and moving to the right and passing Pennsylvania avenue, River street and King avenue to its starting point. It will be noted 55 that the first street after Broadway for an outward bound car is Olive street, but that the space allotted to Olive street on the band A is not disposed immediately following the space allotted to Broadway but that the

space allotted to King avenue is interposed 65 between Broadway and Olive streets. In the same manner the space allotted to Dearborn street does not immediately follow Olive street, though Dearborn street immediately follows Olive street on the map, but that 70 River street on the opposite side of the loop immediately follows Olive. In the same way the space allotted to Pennsylvania avenue is interposed between Dearborn street and Castle street. When the outward bound 75 cars have reached that part of the line where the cars run in both directions, in other words, at Wall street, then the intersecting streets follow in regular order until the intersection of Madison street is reached where 80 the outward bound cars diverge, and here again the spaces allotted to streets on opposite sides of the loop alternate with each other until the loop or diverging track intersects the main track as it may be termed 85 at Clark street after which the spaces allotted to consecutive streets follow each other in consecutive order until Wall street is reached when the car passes to the right and crosses Pennsylvania avenue, River street, 90 King avenue and again reaches the starting point X. When the car reaches the starting point X, one or the other of the reversing solenoids 31 or 32 in Fig. 6 (31^a or 32^a in Fig. 3) is energized which shifts the transmission mechanism so as to put the transmission mechanism in position for a reverse travel of the band when the motor is actuated. Now as the car nears Broadway, the contacts 99 and 97 which are disposed in 100 connection with the trolley wire at that point will be engaged by contacts 36 and 36^a. Through wires 35 or 37 current passes to the solenoid 49 which then closes the motor circuit as heretofore described and the motor 105 is started, winding down the band so as to display the name Broadway and the advertising connected therewith. In other words, the motor continues to run until the perforation 38^b reaches finger 40^b. Then the circuit is closed through magnet 56^a which releases the latch 55, thus breaking the motor circuit. The band has now traveled one 110 space and the word Broadway is displayed, together with advertisements relating to 115 merchants or other business houses located in proximity to this street corner. Just before reaching Olive street which is the next consecutive street crossing, the contacts 36 and 36^a will again engage with contacts 99 120 and 97, the circuit will be again closed through the solenoid 49, and the motor circuit will be again started and the motor will be operated to wind down the band A for another predetermined distance. It will be 125 noted, however, that the next perforation 38^b occurs in the third space, that is, the space c in Fig. 7 and not in the second space or space

b in this figure. Thus the band will continue to wind up while the space *b* is passing and will not stop until the space *c* is reached, then again the finger 40^b will make contact through the perforation 38^b with the contact bar 39 and the circuit through the motor will again be broken. The reason why the stopping of the band will not occur at the space *b* which is a space allotted for King avenue is that King avenue is on the other side of the loop and is the twenty-fourth consecutive street crossing and not the second consecutive street crossing. The same operation occurs for the space allotted for River street. The motor continues to wind up the reel until it is stopped by the finger 10^b coming in alignment with the perforation 38^b and this occurs when the space allotted to Dearborn street is presented at the opening in the casing. This is equally true of the spaces allotted to Pennsylvania avenue and Castle street, but at Wall street where the loop line joins what may be termed the main line, there is a switch which has to be thrown. This switch is thrown by the finger 40 coming in contact with the contact bar 39 as heretofore described through the perforation 38. The finger 40^a also comes in contact with the contact bar 39 at this point but this has no effect inasmuch as the circuit from this finger to the contact bar 39 is broken in consequence of the position of the lever 24. The switch is thrown as heretofore described and the car passes onto the main line. Here the names of the streets on the band A follow each other in consecutive order as will be seen by a comparison of the map in Fig. 8 with the band in Fig. 7. This continues until Madison street is reached when the outward bound car is ready to branch off onto the loop whereupon the switch is again actuated. Here again as in the case of the loop formerly described, the names alternate and again the band is rolled up two spaces at a time instead of one. This continues until the car reaches Clark street when the switch is again actuated and the car passes onto the main line, past Monroe and Randolph streets to the terminus. Here the band reversing mechanism is actuated by the finger 40^a coming in contact with the bar 39 through the perforation 38^a, and upon the return of the car the belt is wound up in a reverse direction to the direction in which it was previously wound. When Clark street is reached, the switch is thrown and the car continues on the main line or street track and the band moves two name spaces at each actuation in a manner heretofore described until Madison street is reached where again the switch is thrown. The car then continues on its way to Wall street and here the switch is thrown directing the car to the right and the car travels past Pennsylvania

avenue, River street and King avenue to the starting point, the belt traveling two spaces for each actuation as before described for this portion of the line.

It will be obvious that the belt may be readily made to travel three spaces if necessary or four, or any desired number for the reason that the belt is only stopped in its travel by the arrival of a perforation opposite the stopping finger 40^b or 40^a. The specimen band illustrated partially in Fig. 7 is of course only a small part of a full band and only shows the band as adapted to the case of a loop line and a straight line of track. As a matter of fact, the band may be adapted to practically any condition of travel.

In Fig. 9 is shown another specimen band which may be used where the total line of track is divided up into sections, certain of the cars traveling to the end of the first section, certain others to the end of the second section, and certain others traveling to the extreme end of the line and back again. It often occurs on lines of this character that a car may for awhile run to the terminus of one of the sections and not along the entire extent of the route, while at other times this same car will travel along the whole route or the greater portion thereof.

It will be seen that in the band A shown in Fig. 3, there are three sections or routes given following each other successively. Notwithstanding the fact that there are three routes placed upon the band, the band will operate only upon the route on which it is set. Thus we will suppose that the band is set for the displaying of names on route 2. Then if the band is traveling upward it will continue to do so until the contact perforation 38^a arrives beneath the finger 40^a whereupon the band will be reversed and will then continue to move downward until the perforation 38^b is reached whereupon the band will again be reversed and will move upward. Now if it is desired that the car shall move over onto route 1 and set the belt on a certain street, the motor is short-circuited by the switch 103, this shifting of the switch at the same operation breaking the battery circuit in wire 58. Under these circumstances the belt keeps on running until the common battery circuit is again closed whereupon the first perforation that comes along stops the belt and it is set ready for duty.

In Fig. 9 the band A illustrated therein is not shown as provided with the perforations 38^b and 38^a nor with the perforations 38 and 38^a as it is not desired to confuse the drawing in this respect.

It is to be understood that while preferably the belt A is formed with perforations 38, etc., through which the contact fingers

may spring into engagement with the contact bar 39, yet I do not wish to be limited to this as the belt might be formed with metallic pieces inset into the belt in any suitable manner which will take the place of these perforations, the current then being conducted from the spring fingers 40, etc., through these contact pieces and to the common contact bar 39. In Fig. 12 I have illustrated a portion of the belt provided with these contacts, these contacts being designated 38' to distinguish them from the perforations. It will be seen that these contacts may be very readily fastened in place either by providing with prongs which will enter the band or fastening the contact plates to the band in any other suitable manner as by rivets, brads, etc.

Preferably the contact fingers are tipped with platinum and preferably each finger is split at its contact end as shown in Fig. 4. This gives a much better and more positive contact than if the finger is solid at the contact end. Thus let a little speck of dirt get on one of the fingers, for instance, and the mechanism might skip one street before the dirt was rubbed off by the moving belt, but by splitting the finger this is overcome as one or the other of the terminal ends of the split finger will always make contact.

It will be seen that my apparatus is relatively simple and that it enables a street name displaying band to be used which can with equal facility be applied either on a straight line, a loop line, diverse route or used where the full route is divided into relatively short sections. Furthermore it is obvious that the mechanism can be used either on a trolley system, third-rail system, or on any system where the power is taken from a conductor extending parallel to the track of a car. The difficulty of apparatus of the kind heretofore produced has been either that it was purely mechanical in its action and that the lost motion incident to practically all mechanical structures prevented the proper coördination of the street names with the proper streets, or that it depended for its operation too much on the human element. Furthermore, these constructions have been very complicated. My improved mechanism is absolutely automatic throughout and yet is very simple in construction, operation and maintenance. It is not necessary to have a single space more on the band than there are actual streets to be crossed. The band is self-reversing and by means of this band each car picks and throws its own switches automatically. The band may be used for advertising matter, the name of each dealer or advertiser being displayed when his actual corner is reached. Attention is also called to the fact that by my construction there is no need of having a single wire

leading out of the case within which the indicator is mounted. There are seven contact plates on the bottom of the case, two adapted to be connected to the battery circuit, two to the car circuit and two to the trolley circuit when the case is slipped in place and one to ground. The outer case or box into which the inner case is slipped also contains six corresponding contact plates so that when the inner case is slipped into place every contact is made instantly. This permits the immediate exchange of one case with its band from one car to another or from one end of the car to the other. These contact plates are lettered D' 80 in the drawings.

One vital point of my invention lies in putting circuit closing means on the band for several purposes and making the band control the stopping and starting of the motor. Another vital element is the reversing lever which cuts in one set of contacts and cuts out the other set of contacts, thus making the one set of perforations in the band active and one set negative or the reverse. It is this reversing lever that makes this form of machine possible and makes it possible to operate a belt showing loop lines in the manner heretofore described. It is also this lever that makes it possible to use this mechanism on third rails, under-ground conduits, etc. In cases where there is a third rail or underground conduit in which the shoe stays always on the same side of the track, two sets of contacts would be applied to the third rail with a corresponding set of two contacts (or four contacts to provide for switch throwing) carried by the car for making contact with the same. These two sets of contacts carried by the car would have two sets of wires one leading to one side of the reversing lever and the other set to the other side of the lever, thus when the lever is thrown in one direction one set of contacts on the third rail would be active when in use, the other set being inactive and vice versa, according to the direction in which the car was going.

The third important feature of my invention lies in the use of alternate spaces on the band for successive streets where the car is traveling over a loop and using the other alternate set of spaces after the band reverses and travels in the opposite direction.

While I have shown perforations in the band for the purpose of closing a circuit between the fingers I want it distinctly understood that it would be equally feasible and is entirely within the purview of my invention to provide metallic contact members disposed in the space occupied by the perforations and exactly the same result would be secured as far as closing a circuit through the fingers is concerned. Again I

do not wish to be limited to the exact form of trolley contact members illustrated, as this trolley contact member might have the form shown in Fig. 11, in which 135 designates the trolley wire and 136 a guy-wire. Suspended from this guy-wire are hanging contact members 137 with which the auxiliary contacts on the trolley pole engage as the car passes a predetermined point.

10 What I claim is:

1. In a mechanism of the character described, a sign displaying band, reels supporting the band, an electric motor, means for actuating said reels through the motor to thereby cause the band to travel, a contact member confronting one face of the band, a pair of contact members confronting the other face of the band and coacting with the first named contact member, means connected in circuit with said contact members for breaking the motor circuit when the circuit is completed by the electrical engagement of either one of the pair of contact members with the first named contact member, said band being divided into a plurality of spaces, each of said spaces having thereon the name of a street, the names of consecutive streets being separated from each other by an intermediate space, the band being provided with means opposite each of the first named spaces whereby a circuit may be closed between one of the contact members of a pair and the first named contact to thereby stop the motor upon the travel of the band in one direction and the band being provided in conjunction with the alternate spaces with means whereby a circuit may be closed between the other of the pair of contact members and the first named contact member to thereby intermittently break the motor circuit upon a movement of the band in a direction opposite to its first movement.

2. In a mechanism of the character described, a sign displaying band, reels over which the band is wound, an electric motor operatively connected to the reels and connected in an interrupted circuit to a source of electric energy, means operated at predetermined intervals to close the motor circuit to thereby cause the actuation of the motor, means for holding the circuit closed to thereby cause the continued reeling up of the band, a pair of contacts disposed on one side of the band and laterally spaced from each other, a contact member disposed on the opposite side of the band and coacting with the first mentioned contacts, a battery, separate electrically actuated means for releasing said holding means each connected in circuit with the battery and with a corresponding one of the first mentioned contacts, the band being provided with means disposed at predetermined intervals for electrically closing the gap between one of

the first mentioned contacts and the contact member, means disposed alternately to the last named means for electrically closing the gap between the other first mentioned contact and the contact member, means for reversing the direction of travel of the band, and means for breaking the circuit between one of the first mentioned contacts and its corresponding electrically actuated means and establishing a circuit between the other first mentioned contact and its electrically actuated means upon a movement of the band in one direction or breaking the last named circuit and establishing the first named circuit upon a movement of the band in the opposite direction.

3. In a mechanism of the character described, a sign displaying band having thereon a series of street names, certain names indicating streets on one portion of a loop route, certain of the names indicating streets on a straight route continuing from the loop, certain other names indicating streets on the other portion of the loop, that portion of the band containing names of streets on the loop route having the names relating to the two portions of the loop in alternate relation to each other, that portion of the band relating to the straight portion of the route having the names of the streets arranged in consecutive order, means for intermittently shifting the band a distance equal to two name spaces while the vehicle is traveling over the loop portion of the route, means for shifting the band intermittently a distance equal to one name space during the travel of the vehicle over the straight portion of the route, and means for reversing the direction of movement of the band at the termini of the route.

4. In a mechanism of the character described, a sign displaying band, an electric motor for moving the band located in circuit with a source of energy, a normally open switch for closing said circuit, a solenoid operatively engaging said switch and when energized acting to close the switch, means urging the switch to open position, means whereby the solenoid may be momentarily energized, a latch adapted to hold the switch closed, a pair of electro-magnets coacting with the latch, either of said magnets when energized releasing it, a local battery, contact members, each connected in an open circuit with the battery and a corresponding one of the electro-magnets, a contact common to the first mentioned contacts and between which and the said first mentioned contact members the band passes, means disposed at predetermined intervals along the band permitting the gap between the first and second mentioned contact members to be closed to thereby energize one or the other of the corresponding electro-magnets and release said switch to break the

motor circuit, means for causing a reversal of the movement of said band when the band has reached the end of its travel in either direction, said means including a shiftable member adapted to break the circuit through one of said electro-magnets and corresponding contacts and close the circuit between the other electro-magnet and its corresponding contacts when in one position or close the circuit through the first named magnet and break the circuit through the second named magnet in its other position.

5. In a mechanism of the character described, a sign-displaying band, an electric motor for moving the band located in circuit with a source of energy, a normally open switch for closing said circuit, a solenoid operatively engaging said switch and when energized acting to close the switch, means urging the switch to open position, means whereby the solenoid may be momentarily energized, a latch adapted to hold the switch closed, a pair of electro-magnets coacting with the latch, either of said magnets when energized releasing it, a local battery, contact members, each connected in an open circuit with the battery and a corresponding one of the electromagnets, a contact common to the first mentioned contacts, and between which and the said first mentioned contact members the band passes, means disposed at predetermined intervals along the band permitting the gap between said contact members to be closed to thereby energize one or the other of the corresponding electromagnets and release said switch to break the motor circuit, electrically actuated means for causing a reversal of the travel of the band when the band has reached the limit of its travel in either direction, said means including a shiftable member, and means carried by said shiftable member for rendering one of said magnets inoperative and rendering the other magnet operative upon a movement of said member in either direction.

6. In a mechanism of the character described, a sign-displaying band, an electric motor for moving the band located in circuit with a source of energy, a normally open switch for closing said circuit, a solenoid operatively engaging said switch and when energized acting to close the switch, means urging the switch to open position, means whereby the solenoid may be momentarily energized, a latch adapted to hold the switch closed, a pair of electro-magnets coacting with the latch, either of said magnets when energized releasing it, a local battery, contact members, each connected in an open circuit with the battery and a corresponding one of the electromagnets, a contact common to the first mentioned contacts, and between which and the said first mentioned contact members the band passes, means disposed at predetermined intervals along the band permitting the gap between said contact members to be closed to thereby energize one or the other of the corresponding electromagnets and release said switch to break the motor circuit, electrically actuated means for causing a reversal of the travel of the band when the band has reached the limit of its travel in either direction, said means including a shiftable member, and means carried by said shiftable member for rendering one of said magnets inoperative and rendering the other magnet operative upon a movement of said member in either direction.

7. In a mechanism of the character described, a sign displaying band, an electric motor in open circuit with said conductor and arranged to move the band, means in circuit with the second mentioned contact and adapted to close the circuit through the motor when the said contact engages the first-named contact, means for holding the circuit closed to thereby cause the continued movement of the band, opposed sets of contacts between which the band passes, electrically actuated means for breaking the motor circuit controlled by the completion of a local circuit through the contacts of either of said sets of contacts, means on the band for causing the completion of the local circuit through either set of contacts to thereby open the motor circuit, means for reversing the movement of the band when it has reached the limit of its travel in either direction, and means connected to and operated by said reversing means for rendering one of said pairs of contacts inoperative and the other operative when the band is reversed.

8. In a mechanism of the character described, a sign displaying band, an electric motor for moving the band connected in an interrupted circuit with a source of energy, a normally open switch for closing said circuit, a solenoid operatively engaging said switch and when energized acting to close the switch, means urging the switch to open position, means whereby the solenoid may be momentarily energized, a latch adapted to hold the switch closed, electro-magnets coacting with the latch and when energized

coacting with the latch, either of said magnets when energized releasing it, a local battery, contact members, each connected in an open circuit with the battery and a corresponding one of the electromagnets, a contact common to the first mentioned contacts, and between which and the said first mentioned contact members the band passes, means disposed at predetermined intervals along the band permitting the gap between said contact members to be closed to thereby energize one or the other of the corresponding electromagnets and release said switch to break the motor circuit, electrically actuated means for causing a reversal of the travel of the band when the band has reached the limit of its travel in either direction, said means including a shiftable member, and means carried by said shiftable member for rendering one of said magnets inoperative and rendering the other magnet operative upon a movement of said member in either direction.

9. The combination with an electric power conductor and with a plurality of contact members connected to said conductor at intervals to receive electricity therefrom, of indicator mechanism including a contact member adapted to engage with the first-named contact members, a sign displaying band, an electric motor in open circuit with said conductor and arranged to move the band, means in circuit with the second mentioned contact and adapted to close the circuit through the motor when the said contact engages the first-named contact, means for holding the circuit closed to thereby cause the continued movement of the band, opposed sets of contacts between which the band passes, electrically actuated means for breaking the motor circuit controlled by the completion of a local circuit through the contacts of either of said sets of contacts, means on the band for causing the completion of the local circuit through either set of contacts to thereby open the motor circuit, means for reversing the movement of the band when it has reached the limit of its travel in either direction, and means connected to and operated by said reversing means for rendering one of said pairs of contacts inoperative and the other operative when the band is reversed.

10. In a mechanism of the character described, a sign displaying band, an electric motor for moving the band connected in an interrupted circuit with a source of energy, a normally open switch for closing said circuit, a solenoid operatively engaging said switch and when energized acting to close the switch, means urging the switch to open position, means whereby the solenoid may be momentarily energized, a latch adapted to hold the switch closed, electro-magnets coacting with the latch and when energized

- releasing it, a local battery, contact members, each connected in an interrupted circuit with said battery and one of the magnets, a contact common to the first mentioned contacts, the band passing between the first and last mentioned contacts, said band having sets of means disposed at spaced intervals, one set of means coacting with one of the first mentioned contacts and
- 10 the common contact and the other with the other first mentioned contact and the common contact to close the circuit, as the band travels, means for reversing the movement of the band, and means for rendering one of the first mentioned contacts operative and
- 15 in coaction with one set of means upon the band while the band is traveling in one direction and rendering the other one of the first mentioned contacts inoperative at this time, or causing said other one of the first 20 mentioned contacts to be operative and the other one inoperative while the band is traveling in the reverse direction.

In testimony whereof I affix my signature in presence of two witnesses.
